UNITED STATES PATENT OFFICE.

WILLIAM HAMILTON WRIGHT, OF BUFFALO, NEW YORK, ASSIGNOR TO
MARY E. WRIGHT, OF BUFFALO, NEW YORK.

BEARING.

SPECIFICATION forming part of Letters Patent No. 729,987, dated June 2, 1903.

Application filed June 17, 1901. Serial No. 64,800. (No model.)

To all whom it may concern:

Be it known that I, WILLIAM HAMILTON WRIGHT, a citizen of the United States, residing at Buffalo, New York, have invented 5 certain new and useful Improvements in Bearings, of which the following is a full, clear, and exact description.

My invention relates to bearings, and particularly to those employing contact-surfaces 10 of the taper or cone-section type.

My invention has for its main objects, first, the substantial elimination of all sliding friction or end thrust; second, the elimination of all cages or separating devices, and, third, to 15 provide an improved taper roller self-contained. In connection with these main objects my invention also provides means to facilitate the setting up of the bearing for locking the bearing in adjustment and for excluding dust and retaining lubricant.

The above-mentioned principal objects combine to eliminate in the largest possible degree frictional contact within the bearing. In seeking to obtain these conditions I have 25 discovered by my experiments that their substantial attainment can be reached by means of placing certain parts of my bearing at particular angular relations, all of which I fully explain and disclose in my specification.

Figure 1 is a longitudinal section of my invention. Fig. 2 is an end elevation, right-hand end of Fig. 1, the internal parts being removed to show the taper rollers in position. Fig. 3 is a detail face view of the washer 21.

This is a typical use of my invention, and its adaptation to other forms of bearings—such, for example, as ordinary shaft-bearings, car-journals, bicycles, and the like—involves the exercise of only ordinary mechanical 35 skill.

1 is a shaft. Upon this shaft are smooth tapering tread-surfaces 2 and 3. These smooth tapering tread-surfaces are so inclined to the axis of the shaft as to form an angle of re- 45 pose, as hereinafter more fully explained, and so as to constitute the inner treads of the bearing. In the drawings herewith the tapering inner tread 2 is integral with the shaft 1, and the tapering inner tread 3 is adjust- 50 able thereon longitudinally; but it will be evident that in other constructions both ta-

pering inner treads may be made separate from the shaft and one or both adjustable, as desired.

4 4 are smooth tapering treads provided 55 with roller-surfaces inclined to the axis of the shaft, so as to form an angle of non-repose, as hereinafter more fully described, and so as to constitute the outer treads of the bearing. These outer treads have their inner ends 60 united by means of a sleeve 5 and have their outer ends turned to cylindrical form and internally threaded to receive the parts herein-after described.

6 6 are ungrooved taper or cone-section 65 rollers which occupy the space between the inner treads and the outer treads.

I will now describe the peculiar construction of the inner treads and the outer treads and the taper rollers and their relation to each 70 other.

The taper or slant of the taper rollers and the taper or slant of the inner treads and the outer treads are such that if their surfaces were continued to form perfect cones 75 their vertices would coincide in the axis of the shaft or axle. The rollers 6 are made to fit the inner and outer treads of the roller-race by this construction, so that each roller is in continuous line of contact with the inner and outer tread of its race, and it has therefore a free-rolling tread over its entire length. The rollers 6 are in "full series"—that is to say, the races are filled with the rollers, except that sufficient space is left between them to prevent their binding or engaging in frictional contact when they are carrying the load or pressure exerted upon the bearing. They are free to rotate on their own axes and to travel in the race. The full 85 series is clearly shown in Fig. 2.

I will now describe the peculiar and essential features of my invention which distinguish it from previous bearings of this class.

I have found that in rolling contact surfaces or treads of this kind there is a certain angle beyond which the taper roller tends to be forced out axially, or "pops," as mechanics express it, and that there is another certain angle within or below which the taper roller tends to feed in axially and to bind. The angle at or beyond which the taper roller

tends to be forced out axially I term a "non-reposing" angle, and the angle at or below which the taper roller tends to feed in or bind I term a "reposing" angle. For example, the 5 angle which the outer tread forms with the shaft is a non-reposing angle and the angle which the inner tread forms with the shaft is a repose angle. If now a repose angle (wherein the tendency of the taper roller is 10 to feed in and bind) is employed for the inner tread and a non-reposing angle (wherein the tendency of the taper roller is to be forced out) is employed for the outer tread, it is evident that such relation of angles may be had 15 that the one tendency is exactly counterbalanced by the other tendency. With this fact in hand I have found what these angles are, and consequently am able to disclose as my discovery a substantially fixed rule or formula 20 for the angles of the parts of a roller-bearing of this class.

The general rule is as follows: The surface of the inner tread should form with the axis of the shaft an angle of substantially fourteen degrees. The surface of the outer tread should form with the axis of the shaft an angle of substantially eighteen and one-half degrees, and consequently the interposed taper rollers in order to be full series and full tread 25 must be tapered at substantially four and one-half degrees. While some departure from these angles may be had and while some variation therefrom may be advisable due to the metal employed or the speed in rotation, 30 I recommend these specific angles, since they constitute a non-reposing angle for the outer tread and a repose angle for the inner tread and the necessary angle for the taper rollers to constitute a counterbalance or counter- 35 poise where the tendency to thrust in the one direction is exactly overcome by the tendency to bind in the other. The angles which I have designated above constitute a counterpoise when the bearing is made of steel and 40 run at ordinary speeds attained by vehicles, line-shafting, and the like.

For facility in setting up the bearing I provide the taper rollers 6 with pins 7 upon their inner ends. Within the outer tread 4 and 45 threaded to the cylindrical portion thereof is a retaining-ring 8, which is flanged, as shown at 9, to an angle corresponding to the outer tread. This flange sets the ring 8 definitely when screwed to place. The ring 8 has an 50 annular trough of sufficient depth and width to form a raceway for the pins 7. When the inner tread is removed, the taper rollers 6 will hang by the pins 7 in the trough of the ring 8, and thus the difficulty of setting up a horizontal bearing of this kind is avoided. The 55 pins 7 and the raceway in which they travel, above described, perform no other function than that of keeping the taper rollers 6 in place while mounting and dismounting the bearing.

In order to prevent the taper rollers from 60 jolting out when free from load, I provide re-

taining-rings 10, which take over the outer ends of the rollers 6. The rings 10 are screw-threaded to the cylinder extensions of the 70 outer treads and are provided with flanges 11, which engage with the outer tread the same as the flanges 9 and for the same purpose. It should be noted that both the retaining-rings 8 and 10 must stand free of the rollers 6 when 75 the rollers are doing work, and they in no sense operate as a cage or race to hold the rollers in position as against end thrust.

In order to adjust the bearings, I provide the adjustable inner tread 3 with a key 12, 80 which prevents its rotation on the shaft 1. The outer portion of the inner tread 3 is threaded internally to receive a threaded ring 13. When the tread 3 is adjusted to place, the key 12 is inserted and the ring 13 is screwed 85 to place against a shoulder on the shaft 1. This prevents the tread 3 from being forced farther inwardly and tightening the bearing. A nut 14 and a washer 15 and a lock-nut 16 are then set up against the end of the 90 tread 3, and it is securely locked. The hub is capped by a cap 17 to exclude dust and to hold the lubricant. A set-screw 18 is provided, by the removal of which the bearing 95 may be charged with lubricant.

To retain the lubricant and exclude the dust from this kind of a bearing, I provide an external washer 19 with an inwardly-projecting portion, which is screw-threaded into the cylinder portion of the outer tread. Upon 100 the inner surface of this inwardly-projecting portion is cut an annular groove, as indicated at 20, to receive a metallic washer 21, which is slotted across its face, as clearly shown in Fig. 3, so that it may be compressed 105 and sprung in place in the annular groove 20. This leaves an annular area between the screw-threaded portion of the washer 19 and the washer 21, and in this space I place a lubricant-retaining and dust-excluding washer, of 110 any desired material, as indicated at 22. In order that this washer may fit closely down upon the shaft 1, I preferably clasp about it a broken ring 23, of any suitable spring material, which will tend to press the washer 22 115 down upon the shaft.

Having thus described my invention and its mode of operation and its adaptation to different uses and without limiting myself to the particular construction herein shown, 120 what I claim is—

1. A taper - roller bearing comprising a smooth, tapering inner tread provided with a roller-surface inclined to the axis of the shaft so as to form an angle of repose, a 125 smooth, tapering outer tread provided with a roller-surface inclined to the axis of the shaft so as to form an angle of non-repose, the inner and outer treads providing a free race between them, and a full series of ungrooved, 130 taper rollers fitted in the free race, held therein from endwise movement by the location of the treads with relation to each other, and having their ends out of contact with any part

- so as to be entirely free thereof, substantially as and for the purposes set forth.
2. A taper-roller bearing comprising a pair of smooth, tapering inner treads each provided with a roller-surface inclined to the axis of the shaft so as to form an angle of repose, a pair of smooth, tapering outer treads each provided with a roller-surface inclined to the axis of the shaft so as to form an angle of non-repose, the inner and outer treads providing free races between them, and full series of ungrooved, taper rollers fitted within the free races, held therein from endwise movement by the location of the treads with relation to each other, and having their ends out of contact with any part so as to be entirely free thereof when carrying the load, substantially as and for the purposes set forth.
3. A taper-roller bearing comprising a pair of smooth tapering inner treads each provided with a roller-surface inclined to the axis of the shaft so as to form an angle of repose, and adjustable with relation to each other as to distance apart, a pair of smooth, tapering outer treads, each provided with a roller-surface inclined to the axis of the shaft so as to form an angle of non-repose, the inner and outer treads providing free races between them, and full series of ungrooved taper rollers fitted in the free races, held from endwise movement by the location of the treads with relation to each other, and having their ends out of contact with any part so as to be entirely free thereof when carrying the load, substantially as and for the purposes set forth.
4. In a taper-roller bearing, in combination with smooth tapering inner treads provided with roller-surfaces inclined to the axis of the shaft so as to form angles of repose, and smooth tapering outer treads provided with a roller-surface inclined to the axis of the shaft to form angles of non-repose, and full series of ungrooved taper rollers; means for taking down and setting up the bearing, comprising pins on the inner ends of said taper rollers, sleeves threaded to the inner ends of the outer treads and provided with annular grooves to receive the pins on the ends of

said taper rollers and within which the same are free to travel, so that when the shaft and inner treads are removed the taper rollers will be held substantially in place so that the shaft and the inner treads may be replaced as and for the purposes set forth.

5. In a taper-roller bearing, in combination with smooth tapering inner treads provided with roller-surfaces inclined to the axis of the shaft so as to form angles of repose, and smooth tapering outer treads provided with a roller-surface inclined to the axis of the shaft to form angles of non-repose, and full series of ungrooved taper rollers, means for adjusting the said bearing, comprising a threaded ring threaded to the inner surface of one of the inner treads and bearing against a shoulder on the shaft to hold the said inner tread against further movement toward the opposite inner tread, a nut threaded to the shaft setting against the outer end of said inner tread, and a washer and check-nut for holding the same against turning, substantially as and for the purposes set forth.

6. In a taper-roller bearing, in combination with smooth tapering inner treads provided with roller-surfaces inclined to the axis of the shaft so as to form angles of repose, and smooth tapering outer treads provided with a roller-surface inclined to the axis of the shaft to form angles of non-repose, and full series of ungrooved taper rollers, means for retaining the lubricant in said bearing and for excluding the dust, comprising a washer screw-threaded to one of said outer treads, and inwardly-extending portion on said washer carrying a metallic washer, and a lubricant-retaining and dust-excluding washer interposed between said first-mentioned washer and said last-mentioned washer, substantially as and for the purposes set forth.

In witness whereof I have hereunto set my hand, in the presence of two witnesses, this 11th day of June, 1901, at the city of Buffalo, in the county of Erie and State of New York.

WILLIAM HAMILTON WRIGHT.
